UNITED STATES PATENT OFFICE

GEORGE P. BERGER, OF BELLEVILLE, NEW JERSEY

PAINT STRAINER

Application filed May 31, 1930. Serial No. 458,398.

This invention relates to paint strainers or contrivances for similar purposes. It consists of a cover with inlet for paint, or other liquid material, to which cover is clamped the straining devices or body which is built up of thin rings separated by washers at the ears of the rings. The washers keep the rings apart sufficiently to allow only the desired fine material through and retain the coarse material within the central cylindrical chamber formed by the rings. This invention includes also scrapers mounted upon a shaft kept concentric with the straining chamber by centering the rings at the top and bottom. These scrapers are thin material inserted between the strainer rings and when rotated by the shaft to which they are attached they scrape away from the rings any foreign or coarse material which has lodged there, allowing other material of proper fineness to pass through. The fine material upon passing between the rings, enters the chamber of the receptacle forming the outer casing around the strainer rings, then out through the outlet into suitable containers. The coarse material is retained within the central cylindrical chamber and drops or settles to the bottom. The bottom has an opening and a cupped closure removable to facilitate cleaning.

This invention is believed to comprise parts of special and novel construction and disposition as set forth in the accompanying drawings.

Of the drawings Fig. 1 represents a side view chiefly in vertical section showing all parts assembled. Fig. 2 is a top view of one strainer ring. Fig. 3 is a top view of a strainer ring, showing the position of the spacing members or washers, and showing also the position of the scrapers with respect to the rings. Fig. 4 is a top view of one of the scraper spacer pieces.

Throughout the drawings and description the same number is used to refer to the same part.

Consider the drawings, a receptacle 1 has a removable top 2 provided with an inlet opening and inlet chamber 3. The receptacle has an outlet 4 in its lower wall, and a re-

movable bottom closure 5 covering an opening in the bottom surrounded by the vertically and interiorly projecting flange 6. A flanged ring 7 engages the flange 6, and on ring 7 are piled one above another any number of strainer rings 8 formed with radially extending pierced ears 9 as best shown in Fig. 2. The rings are spaced apart by members or washers 10, and bolt rods 11 pass upwardly through the ear rings, spacing members, the base ring 7 and top 2, whereby the rings are supported and held centrally in the receptacle. A central cylindrical vertical chamber is formed in the ring pile.

The form and position of the scrapers 12 is best shown in Fig. 3, and the form of the scraper spacing pieces 13 is illustrated in Fig. 4. By means of a screw 15 or in any convenient way the pile of scrapers and pieces are secured to a central shaft 16, and the scraper pile is further held together by the vertical bolt rod 14 which bolt rod passes also through a scraper centering or base ring 18 concentric with the bottom opening flange 6. The central shaft 16 passes downwardly through the openings provided therefor in scrapers 12 and spacing pieces 13, and the scrapers and spacers one above another are clamped together upon the shaft 16 by the nut 17 as shown in Fig. 1, against the inwardly projecting portion of ring 18. Thus the central cylindrical chamber that is formed by the pile of strainer rings is continued downwardly into the flange 6 to the opening in the bottom of the receptacle stopped by the closure 5.

As shown in Figs. 1 and 3 the scrapers 12 are spaced apart by the interposed pieces 13, and a bolt rod 14 passes upwardly through the scraper centering ring 18, through the scrapers and spacing pieces and binds the scrapers and spacers together. It will be also observed that the central shaft 16 passes out through the top of the receptacle 1, and, as the strainer rings pile is attached to the top 2, and the scraper pile to the shaft 16 both the strainer rings pile and the scraper pile may be withdrawn together from the receptacle and replaced without changing the relative positions of those interior parts.

In the operation as stated the fine material passes from the center outwardly between the strainer rings, and the coarse material is gathered by the scrapers into the central 5 chamber and settles into the closure 5 which can be removed and cleaned at desired intervals. It is believed that the parts herein illustrated and described disclose a combination of elements of special formation and 10 arrangement and of superior usefulness for the purpose set forth.

Having now described this invention and explained the mode of its operation, I claim:—

- 15 15 A paint strainer having in combination, a receptacle, a removable top therefor having a paint inlet, an outlet provided for the receptacle, the bottom of said receptacle having a central opening and an upwardly ex-
20 20 tendsing flange surrounding the said opening, removable bottom closure for the said opening, a pile of strainer rings, spacing members for said rings, means for supporting the rings concentrically with respect to the
25 25 said bottom flange, a revolute shaft, a scraper centering ring on the lower end of said shaft, a pile of scrapers carried by said ring, spacing pieces arranged between said scrapers, the said scrapers extending mov-
30 30 ably between the said strainer rings, and the said rings, scrapers and shaft being attached to and removable with the said top.

In testimony whereof I affix my signature.
GEORGE P. BERGER.
